United States Patent Office.

GEORGE BYRON KIRKHAM, OF NEW YORK, N. Y.

Design No. 3,571, dated July 6, 1869.

DESIGN FOR A WINDOW-FASTENING.

The Schedule referred to in these Letters Patent and making part of the same.

To all whom it may concern:

Be it known that I, GEORGE BYRON KIRKHAM, of 167 East Thirty-Third street, in the city of New York, in the county of New York, and State of New York, have originated and designed a new Window-Fastening, of which the following is a full, clear, and exact description, reference being had to the accompanying drawing, making part of this specification, in which the fastening is represented complete in its proper position in a window-casing.

It consists of a long arm, A, with an ornamental handle or knob, F, and a short arm, having two sharp-pointed ends B C, and a pivot, D.

What I claim as my invention, and desire to secure by Letters Patent, is—

The design for a window-fastening, herein set forth.

GEO. B. KIRKHAM.
